UNITED STATES PATENT OFFICE.

LLEWELYN WATERS, OF EDWARDSDALE, PENNSYLVANIA.

LUBRICATOR.

SPECIFICATION forming part of Letters Patent No. 728,146, dated May 12, 1903.

Application filed November 13, 1902. Serial No. 131,240. (No model.)

To all whom it may concern:

Be it known that I, LLEWELYN WATERS, a citizen of the United States, residing at Ed-
wardsdale, in the county of Luzerne and State
of Pennsylvania, have invented certain new
and useful Improvements in Lubricators; and
I do hereby declare the following to be a full,
clear, and exact description of the invention,
such as will enable others skilled in the art to
10 which it appertains to make and use the same.

This invention relates to improvements in
lubricators.

The object of the present invention is to im-
prove the construction of a gravity-feed oil-
cup and to provide a simple, inexpensive, and
15 efficient one which will be positive and reliable
in operation and in which the ball is re-
movably secured.

The invention consists in the construction
20 and novel combinations fully described, illus-
trated in the accompanying drawings, and
pointed out in the claims hereunto appended.

In the accompanying drawings, Figure 1 is
25 a vertical cross-sectional view of an oil-cup
constructed in accordance with my invention
and applied to a journal-box. Fig. 2 is a per-
spective view of the removable diaphragm or
seat. Fig. 3 is a perspective view of the ball-
valve.

30 Like numerals of reference designate corre-
sponding parts in all the figures of the draw-
ings.

1 is a journal-box having therein a jour-
nal 2, and the reservoir of the oil-cup 3 is de-
35 tachably secured to the journal by means of
a screw-threaded hollow shank or tube 4,
which is formed integral therewith. A hexa-
gon-shaped nut 5 secures the oil-cup in a
locked position upon the journal-box. An
40 ordinary cap 6 is provided for the oil-cup. A
removable cylindrical seat member 7 has an
annular groove 8 for receiving any suitable
packing, which acts as a retaining means for
the seat and at each of its ends has formed a
45 concaved cut-out portion 9, which is adapted
to receive the ball-valve 10 when the seat 7 is
forced upon the same in the hollow shank 4.
The ball-valve 10 is retained in the shank 4

by means of the flanged edges 11 of the hol-
low shank and the removable seat 7. The 50
packing 12 is of such thickness and quality
as to retain the seat 7 in the hollow shank,
and said seat is adapted to continually bear
against the ball-valve 10, whereby the said
valve is held against the journal 2, as shown 55
in the drawings, Fig. 1. An aperture 13 in
the seat 7 permits of the passage of the oil
when the ball-valve is rotated.

The invention has the following advan-
tages: The seat will permit of the removal of 60
the ball-valve without injury to the oil-cup,
and when the ball-valve becomes gummed or
its rotation becomes otherwise impaired it
can be cleaned, as well as the inside of the
hollow shank. Owing to the construction of 65
the seat it can be replaced in said hollow
shank and either of its ends can be forced
upon the ball-valve.

Changes in the form, proportion, and minor
details of the construction may be resorted to 70
without departing from the spirit or sacrific-
ing any of the advantages of this invention.

Having thus fully described my invention,
what I claim as new, and desire to secure by
Letters Patent, is—

75 1. In an oil-cup including a reservoir and a
hollow shank formed integral therewith, a
ball-valve seated within the shank, a remov-
able seat in said shank, having concave ends,
and an annular groove formed on its periphery 80
and suitable means in said groove for retain-
ing said seat within the hollow shank, sub-
stantially as described.

2. In an oil-cup including a reservoir and a
hollow shank formed integral therewith, a 85
ball-valve seated within the shank, a remov-
able seat in said shank, having an annular
groove and suitable packing contained there-
in, whereby the seat is retained against the
ball-valve, substantially as described. 90

3. In an oil-cup including a reservoir and a
hollow shank formed integral therewith, a
ball-valve seated within said shank, a remov-
able seat having concave ends adapted to
bear against said ball-valve, and suitable 95
means for retaining said seat in contact with

the valve, whereby the said valve is held against the journal.

4. In an oil-cup including a reservoir and a hollow shank, an inwardly-extending flange formed integral therewith on its outer end, a ball-valve seated within said shank, a frictionally-secured cylindrical seat member retained within the shank and securing the ball-

valve in contact with the journal, substantially as described.

In testimony whereof I hereunto affix my signature in presence of two witnesses.

LLEWELYN WATERS.
